UNITED STATES PATENT OFFICE.

ALFRED PIRTLER, OF LOUISVILLE, KENTUCKY.

DESIGN FOR A SPOON.

SPECIFICATION forming part of Design No. 24,467, dated July 16, 1895.

Application filed March 23, 1895. Serial No. 542,990. Term of patent 3½ years.

To all whom it may concern:

Be it known that I, ALFRED PIRTLER, a citizen of the United States, residing at Louisville, in the county of Jefferson and State of Kentucky, have invented and produced a new and original Design for Souvenir Spoons, of which the following is a specification, reference being had to the accompanying drawings, showing the spoon as designed.

Figure 1 is a view of the front of the spoon, showing my design. Fig. 2 is a side elevation of the same; and Fig. 3, a view of the back of the design, these three views being deemed necessary to fully illustrate my design.

I have endeavored to use a tobacco-plant as the base of my design.

In Fig. 1 the handle of the spoon at the end is formed to represent a bit of earth clinging to the roots of a tobacco-plant. The bowl of

the spoon is almost a section of a sphere and 20 of the proper depth and is ornamented by the leaves of the tobacco-plant in relief when starting from the stem or handle of the spoon, but flattened out in the bowl, where the flowers of the plant are shown. The bunch of 25 leaves covers a part of the front and back, as shown. The leaves are shown in relief on the sides of the bowl, as in Fig. 2. Smaller leaves are shown on the stem, as indicated in Figs. 1, 2, and 3. The back of the bowl of 30 the spoon has space for an inscription.

What I claim is—

The design for a spoon, as herein described and shown.

ALFRED PIRTLER.
